US00D663855S

(12) United States Design Patent
Zack et al.

(10) Patent No.: US D663,855 S
(45) Date of Patent: * Jul. 17, 2012

(54) SAUNA EXTERIOR

(75) Inventors: Aaron Zack, Overland Park, KS (US);
Doug Vandervalk, Overland Park, KS (US); Jasen Sappenfield, Overland Park, KS (US)

(73) Assignee: Sunlighten, Inc., Overland Park, KS (US)

() Term: 14 Years

(21) Appl. No.: 29/356,445

(22) Filed: Feb. 25, 2010

(51) LOC (9) Cl. 23-02

(52) U.S. Cl. D24/203

(58) Field of Classification Search D24/201-205;
4/524, 526, 528, 531, 532

See application file for complete search history.
